(57) **CLAIM**

I claim the ornamental design for a domed structure, substantially as shown and described.

DESCRIPTION

FIG. 1 is a front perspective view of a domed structure in accordance with the present design;

FIG. 2 is a front elevational view thereof, with rear view being identical;

FIG. 3 is a right side elevational view thereof, with the left side view being identical;

FIG. 4 is a top plan view thereof; and,

FIG. 5 is a bottom plan view thereof.

The broken lines represent portions of the domed structure which form no part of the claimed design.
